Attorney.

UNITED STATES PATENT OFFICE.

ASHER B. STEVENS, OF NEW BRIDGE, NEW JERSEY, ASSIGNOR, BY MESNE ASSIGNMENTS, TO THE ROCKER SPRING COMPANY, OF CHICAGO, ILLINOIS.

SPRING ATTACHMENT FOR ROCKING-CHAIRS.

SPECIFICATION forming part of Letters Patent No. 440,516, dated November 11, 1890.

Application filed June 22, 1886. Serial No. 205,889. (No model.)

To all whom it may concern:

Be it known that I, ASHER B. STEVENS, a citizen of the United States, residing at New Bridge, in the county of Bergen and State of New Jersey, have invented certain new and useful Improvements in Spring Attachments for Rocking-Chairs, of which the following is a full, clear, and exact description.

This invention relates to the now common connection for the rocking portion and base of the class of chairs designated "base" or "platform" rockers or rocking-chairs, which connection comprises a closely-coiled spring about as broad as long, or of greater diameter than length, and having its end coils firmly connected to metallic brackets, which in turn are attached to the base and rocking portions of the chair, respectively, two or a set of such connections being applied to the chair within its base and rockers and serving to unite the base and rocker portions and at the same time permit the free rocking motion against the tension of the spring, the recovery of the spring assisting in restoring the rocking portion to balance, all as usual in this class of devices.

My invention consists in a spring-attaching bracket for rocker-springs in which the sole has arms projecting from the base-plate to such a length as to receive the end coils of the spring or springs within them for over half the circumference of the spring, so that when once in place the spring cannot work loose, but will be rigidly held in engagement with the bracket.

The invention also consists in various details of construction, substantially as herein-after particularly set forth and claimed.

In the accompanying drawings, in the several figures of which like parts are similarly designated, Figure 1 is a front elevation of one of my improved spring-connections with the lower part of the spring broken away. Fig. 2 is a plan view, Fig. 3 a vertical section, Fig. 4 a modification in plan view, and Fig. 5 a plan, of a twin or compound spring connection.

The mode of applying devices of the class to which mine appertains is so well known that I have deemed it unnecessary to show and describe the parts of a chair of the kind to which my invention is applicable.

The spring *a* may be of the usual kind employed in this class of devices—viz., of stiff spring-wire coiled to shape, with its several coils resting and binding directly upon one another and acting by extension and deflection. The bracket to receive this spring has a base or plate *b* of suitable construction to enable it to be attached to the appropriate parts of a chair. The sole *c* projects from the base, as usual in brackets, but describes the curvature of a spiral co-ordinate with the spirality of the spring it is to receive, substantially as indicated in Fig. 1, where the spring is broken away to show this feature. This sole is extended or projects from the plate, as arms *d d*, to an extent greater than half the circumference of the spring they receive, and they follow the line of curvature of the spring, as in Figs. 1, 2, 3, and 5, or they may be tangent to the diametrical points of the spring, as in Fig. 4. These arms have the external vertical flanges *e* to prevent lateral displacement of the springs. The ends of the arms *d d* are preferably beveled or tapered, so as to facilitate the attachment of the spring to the bracket, and this connection is effected by simply forcing the arms and sole of the bracket between the end coils of the spring, so that after the spring has passed into the sole and arms beyond its diameter it snaps right into place and cannot be removed except by force and by prying open or lifting its end coil. For additional security and to prevent any possibility of the spring turning on its own axis on or in the bracket, I provide a notched web *f* on the inside of one arm and enter into said notch the indent end *g* of the spring. This absolutely prevents any accidental dislocation of the spring, though it might be dispensed with, as indicated in Fig. 4.

In Fig. 5 I have shown these same features applied to a duplex or twin-spring attachment.

In my invention the spirality of the sole and arms conforming to the spirality of the spring it follows that the spring must stand straight, and hence there is no need of rights and lefts.

With my present construction of the spring retaining and embracing arms extending from the bracket a distance greater than half the

circumference of the spring I am enabled to hold the spring by its sides only, and need no intermediate engaging device.

Instead of bending inward the end of the 5 spring to engage the notched web, it may be bent outward to engage a notch in the outer rim or flange. This deflected end of the spring in either case is snapped into its notch or depression and is held there by the force of 10 the spring.

In my application, Serial No. 190,082, filed 15 January 28, 1886, I have laid claim, broadly, to the engagement of the spring and bracket by deflecting the end of the spring, and therefore do not claim the spring herein.

What I claim is—

1. A spring-attaching bracket for rocker-springs in which the sole of the bracket has spring-embracing arms projecting from it a 20 distance greater than half the circumference of the spring to be held thereby, the opposite spring-holding points on the arms of the

bracket on the same side of the diameter of the spring parallel to the face of the plate being nearer together than the extremes of 25 such diameter, substantially as described.

2. A bracket having a plate, a sole, arms projecting from said sole forward of and beyond diametrical points next said arms, the opposite spring-holding points on the arms of 30 the bracket on the same side of the diameter of the spring parallel to the face of the plate being nearer together than the extremes of such diameter, and flanges on the outer edges of said arms to hold and retain the spring to 35 and on the bracket against motion in any direction, substantially as described.

In testimony whereof I have hereunto set my hand this 17th day of June, A. D. 1886.

ASHER B. STEVENS.
